E. E. BOLES

STEAM CLEANER FOR MOTORS

Filed Nov. 17, 1923

Inventor
E. E. BOLES
By Victor J. Evans
attorney

UNITED STATES PATENT OFFICE.

ELZIE E. BOLES, OF SANTA ANA, CALIFORNIA.

STEAM CLEANER FOR MOTORS.

Application filed November 17, 1923. Serial No. 675,376.

To all whom it may concern:

Be it known that I, ELZIE E. BOLES, a citizen of the United States, residing at Santa Ana, in the county of Orange and State of California, have invented new and useful Improvements in Steam Cleaners for Motors, of which the following is a specification.

This invention relates to steam cleaners for motors and has particular reference to means for creating a jet of steam for the purpose of blowing the same through the cylinders to clean out the carbon therein.

Another object is to produce a device of this character which is simple in construction, cheap to manufacture, and well within the purchase price of the average user.

Another object is to produce a device which may be attached to any automobile now upon the market without materially altering the construction of the same.

Other objects and advantages will be apparent during the course of the following description.

In the accompanying drawings forming a part of this specification, and in which like numerals are employed to designate like parts throughout the same,

The figure is a side elevation of a motor having my device attached thereon.

It is a well-known fact that live steam driven through the cylinders of an internal combustion engine will clean out and blow out the carbon which may be deposited there-

in. I have sought to provide means whereby steam may be quickly generated and blown through the various cylinders, as desired.

In the accompanying drawings wherein for the purpose of illustration is shown a preferred embodiment of my invention, the numeral 5 designates a motor as a whole having an exhaust pipe 6. This exhaust pipe is connected to the usual exhaust ports 7, 8, 9 and 11, while the customary spark plugs 12 and 13 serve to ignite the charge in two of the cylinders, while in the drawing the spark plugs in two of the other cylinders have been removed and auxiliary valves 14 and 16 have been inserted in their place. It is of course obvious that a spark plug of the type having a port and valve incorporated therein would eliminate the necessity of removing the spark plug.

To the lower end of the exhaust pipe or exhaust manifold is attached a casting, which

casting has a passageway 18 extending directly therethrough and in line with the bore of the exhaust manifold. A chamber 19 is offset from the passageway 18 and has access thereto through the medium of ports 21 and 22. These ports may be closed by flap valves 23 and 24.

A coil preferably made of copper is positioned in the chamber 19 and bears the numeral 26. This coil has its lower extremity connected by a pipe 27 to a T fitting 28. This T is also connected to a reservoir 29 and has its other connection extending by a pipe 31 to the valve 16. The opposite end of the coil 26 is connected by a pipe 32 to the valve 14.

The operation of my device is as follows:—

When it is desired to clean a cylinder the flap valves 23 and 24 are moved into the position shown in the figure. The engine is then started, with the result that the exhaust from the left-hand cylinders will be conducted from the exhaust manifold through the chamber 19 around the coil 26 and thence through the port 22 to the exhaust pipe for discharge. At the same time the working of the right-hand cylinders will cause air to be forced through the pipe 31 to the pipe 27, and at the same time a small amount of liquid will be taken from the reservoir 29 and shot into the hot coil 26, thus forming a super-heated steam which will then pass to the cylinder having the valve 14 secured thereto.

When it is desired to clean the other cylinders the pipes 31 and 32 will be removed to the respective cylinders. When desiring to remove dirt or grease from the outside of the motor, disconnect the pipe 32 and then connect the steam hose.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having thus described my invention, I claim:—

1. In a device of the character described, the combination with a motor, a casting adapted to be secured to the exhaust manifold of said motor, said casting having a chamber formed therein, a coil mounted in

said chamber, means for conducting vapor to said coil, and means for discharging said vapor into one of the cylinders of said motor.

2. In a device of the character described, 5 the combination with an internal combustion engine having an exhaust manifold, a casting secured to said manifold and adapted to receive the exhaust therefrom, a passageway formed in said casting, a chamber formed in 10 said casting, ports formed in said chamber and communicating with said passage, flap valves adapted to close said ports, a coil mounted in said chamber, and means for conducting a vapor to and away from said 15 coil, for the purpose specified.

3. In a device of the character described the combination with an engine of the internal combustion type, means for conducting a jet of steam to the cylinders of said engine individually, said means comprising a coil, a receptacle adapted to contain a quantity of fluid, means for conducting a small portion of said fluid to said coil, means for conducting said fluid from said coil to said cylinders independently, and means for heating said coils from the exhaust of said cylinders, substantially as and for the purpose specified. 20 25

In testimony whereof I affix my signature.

ELZIE E. BOLES.
